UNITED STATES PATENT OFFICE

FRANK N. SILVA, JR., OF SANTA MARIA, CALIFORNIA

WHEEL ATTACHMENT FOR SEAPLANES

Application filed March 14, 1929. Serial No. 347,054.

This invention relates to aircraft and has for its object the provision of means under the control of the pilot whereby a seaplane may be arranged to effect a landing or a take off upon land as well as upon the water. 5 The invention provides landing gear which will be normally housed within the pontoons or floats of the seaplane so as to avoid excessive head resistance but which may be easily 10 projected to working position by fluid pressure manipulated from the cock pit of the fuselage. The invention provides means whereby the landing wheels may be projected through the bottom of the pontoons or floats 15 and when the landing wheels are withdrawn the bottoms of the floats or pontoons will be closed so as to avoid wind resistance. Other objects of the invention will appear incidentally in the course of the following description, and the invention resides in certain 20 novel features which will be particularly pointed out in the appended claims.

In the annexed drawings:

Figure 1 is a view somewhat diagrammatic 25 in character showing a seaplane having the present invention embodied therein,

Fig. 2 is a similar view showing the seaplane in side elevation,

Fig. 3 is an enlarged longitudinal vertical 30 section of a landing wheel and the parts immediately associated therewith.

Fig. 4 is a view, partly in front elevation and partly in section, on the line 4—4 of Fig. 3,

Fig. 5 is a diagrammatic view showing the 35 means for controlling the pressure fluid, and

Fig. 6 is an enlarged detail section on the line 6—6 of Fig. 4.

In the drawings, the reference numeral 1 40 indicates the fuselage of a seaplane and the numeral 2 indicates floats or pontoons which may be of any approved form and which are connected with the fuselage by struts, indicated conventionally at 3. In carrying out 45 the present invention, the pontoon or float is provided in its bottom with an opening through which the landing wheel 4 may be projected and this opening is normally closed by doors 5 hinged to the side portions of the 50 bottom of the float to swing on axes extending

longitudinally of the float. Adjacent the doors and near the side walls of the float or pontoon, bracing posts 6 are secured in vertical position rigidly to the pontoon, as shown most clearly in Fig. 4. Pivoted to each bracing post 6 is the front end of a link 7, the links converging inwardly and rearwardly, as will be understood upon reference to Fig. 4, and having their rear ends fitted to the ends of the axle 8 upon which the landing wheel 4 is mounted, and also pivotally engaged with the ends of said axle is a fork 9 which extends upwardly and spans the wheel and passes through a longitudinal slot 10 in the top of the float, the crown of the fork being enlarged to acquire strength and being welded or otherwise intimately united with the lower end of a piston rod 11. The piston rod 11 carries a piston 12 on its upper end and said piston plays in a cylinder 13 which is supported on the top of the float and is provided with ports 14 in its upper and lower ends. The lower end portion of the cylinder is enlarged, as indicated at 15, so as to provide the requisite strength and upon this enlarged portion at diametrically opposite points are formed or permanently attached spherical lugs 16 on the outer ends of short studs 17 which project laterally from the cylinder. The knobs or spherical enlargements 16 are 50 fitted within casings 18 having longitudinal slots 19 in their sides presented to the cylinder 13, the stems 17 passing through the said slots and being adapted to play along the same. Both ends of the casings 18 are closed and, above and below the knobs 16, springs 20 and 21 are mounted in said casings, the upper springs 20 being stronger than the lower springs 21. The casings 18 are rigidly secured to or formed integral with pedestals 90 or brackets 22 which are rigidly secured upon the top of the float and the cylinder 13 is disposed between the casings and out of contact therewith so that it may have a rocking movement about the knobs 16 as a center to 95 accommodate the angular movement of the piston rod and the fork 9 as the landing wheel is projected or retracted.

Hose 23 are fitted to the respective ports 14 in the heads of the cylinder 13 and said hose 100

are connected with and form extensions of pipe lines 24 which extend into the cock pit of the fuselage, as will be understood upon reference to Fig. 1. Branch lines, indicated at 5 25, extend to the cylinder 26 of a pump which is mounted within the fuselage and is adapted to effect circulation of the oil with which the pipe lines are filled so as to act upon the piston 12 and thereby raise or lower the landing wheel as may be desired. Within the 10 cylinder 26 is a piston 27 fitting closely therein and the opposite ends of the cylinder are in direct communication with the respective branch lines 25, as shown in Fig. 5. The piston 27 is secured upon a piston rod 28 extending through one end of the cylinder and connected to a crosshead 29 slidably mounted in ways 30. The crosshead 29 has pivoted thereto a pitman 31 which has its outer end 15 connected to a crank disk 32 driven from a motor, indicated conventionally at 33. Within the cock pit of the fuselage, the branch lines 25 are each formed with or connected to a lateral pipe 34 and interposed in the 20 pipes are three-way valves 35 which may be of any well known form and are operable in a well understood manner to control the direction of flow of the pressure fluid.

As shown in Figs. 3 and 4, the landing 30 wheel 4 is normally housed within the float and rests upon the doors 5 at the meeting edges of the latter. On its inner side adjacent its hinged edge each door is provided with a tapered enlargement 36 and immediately adjacent the lower side of said enlargement the lower end of a tension spring 37 is connected to the door. The upper end of each tension spring is secured to a cable 38 which extends upwardly and is attached to a 35 retracting spring reel 39 mounted in any convenient manner upon the respective link 7. The spring reel exerts a constant pull upon the cable 38 to hold the attached door 5 raised and closed and the tension spring 37 serves 40 to keep the cable taut so that the desired action will be attained with certainty. When the landing wheel is projected, the doors will automatically swing downwardly and the links 7 will also swing downwardly, as indicated by the dotted lines in Fig. 3, and will project through the door opening and engage against the inner sides of the respective doors, as indicated by the dotted lines in Fig. 4. The doors will thus be held open when 45 and as long as the landing wheel is projected. When the landing wheel is retracted, the cables 38 are automatically retracted so that the doors will close as the landing wheel moves upwardly. The enlargements 36 on the doors are so located relative to the springs 37 and cables 38 that, when the doors are 50 opened and the landing wheel is in its working position, the springs and cables will be curved over said enlargements and, consequently, be so disposed as to readily exert the

desired withdrawing pull upon the doors as the wheel is raised.

It will be readily noted that the pipe lines carrying the oil or other pressure fluid are connected with the opposite ends of the cylinder 13, check valves 40 being provided in the couplings which connect the pipes with the cylinder, and a similar valve 41 being provided in the piston. When the piston moves toward the motor, the oil may flow through the piston but when the piston moves in the opposite direction, the oil will be subjected to pressure and caused to circulate. The direction of flow to and from the cylinders 13 is controlled by the valves 35 which may be mounted upon a common control post or board within the cock pit. When the valves are set to direct the flow into the upper end of the cylinder, the pressure of the oil or other fluid will cause the piston 12 to move downwardly and the wheel will be projected, the oil below the piston 12 simultaneously moving out through the lower end of the cylinder and returning into the circulating system. Of course, a reverse flow of the oil will raise the landing wheel. As the landing wheel moves downwardly, it will swing in an arc having the front ends of the links 7 as a center and will, therefore, have a slight relative rearward movement, which movement is accommodated by the mounting of the cylinder 13 with the knobs 16 and the provision of the slot 10 in the top of the float. When the wheel is projected and a landing effected on the ground, the landing shock is absorbed by the oil or other pressure fluid within the cylinder 13 above the piston 12 and also by the springs 12 in the casings 18, the cylinder 13 being permitted to yield upwardly to the impact of the wheel upon the ground and this upward movement being absorbed and checked by the upper stronger springs 20. When the landing has been effected, the recoil or settling of the landing wheel and the other parts will be absorbed by the lower buffer springs 21 in the casings 18, as will be understood.

It will be understood that, while in the foregoing description I have referred to only a single landing wheel and its connections, a landing wheel is provided in each float or pontoon with which the plane is equipped and that the several landing wheels and the operating mechanisms are duplicates. The mechanism embodying my invention is very simple and is highly efficient. When the landing wheels are in their inoperative positions, they are entirely housed within the pontoons so that they do not add to the wind resistance in any degree and the cylinders and supporting pedestals upon each pontoon or float may be enclosed in a stream line casing so that the wind resistance offered by these parts will be minimized. In the drawings, however, I have not illustrated a hous-

ing around these cylinders in order that the arrangement and construction of the parts may be more readily understood.

Having thus described the invention, I claim:

5. 1. In a seaplane, the combination with a pontoon having a door opening in its bottom, of doors adapted to close said opening, links pivotally mounted within the pontoon, a landing wheel carried by said links, means for lowering and raising the wheel, and flexible connections between the doors and said links whereby the doors will be closed as the wheel is raised.
15. 2. In a seaplane, the combination with a pontoon having a door opening in its bottom, of swinging doors arranged to close said opening and each provided on its inner side with an enlargement having a convex surface, links pivotally mounted within the pontoon, a landing wheel carried by said links, means connected with the links for lowering and raising the wheel, and flexible connections between the links and the doors whereby the doors will be closed as the wheel is raised, said flexible connections being located adjacent the enlargement on the doors whereby to rest on said enlargements when the doors are opened and the links being arranged to extend through the door opening and bear against the doors at the sides of the wheel when the wheel is lowered.
25. 3. In a seaplane, the combination with a pontoon, of links pivotally mounted at their front ends within the pontoon, a wheel carried by the rear ends of the links and adapted to move downwardly and upwardly through the bottom of the pontoon, a cylinder supported on the pontoon for rocking movement, a piston mounted in said cylinder, a piston rod extending from the piston through the lower end of the cylinder, a fork carried by the lower end of the piston rod and connected with the rear ends of the links, and means for supplying fluid pressure to the cylinder through either end thereof to play upon the piston.
35. 4. In a seaplane, the combination with a pontoon, of pedestals mounted on the top of the pontoon, casings fixed to the inner sides of said pedestals and provided with longitudinal slots in their inner sides, a cylinder disposed between said casings and having lateral stems projecting through the slots in the casings, knobs on the outer ends of said stems within the casings, expansion springs within the casings above and below said knobs, a landing wheel disposed within the pontoon, a swinging support for said wheel, a piston mounted within the cylinder, connections between the piston and the swinging support for the wheel, and means for delivering fluid pressure to the cylinder through either end thereof to play upon the piston

whereby to lower and raise the landing wheel.

5. In a seaplane, the combination with a pontoon, of a landing wheel normally housed in the pontoon, a fluid-pressure controlled piston operatively connected with the wheel for lowering and raising the same, and a cylinder mounted on the pontoon and housing the piston, the cylinder being mounted to rock for accommodating angular movement of the wheel in raising and lowering.

6. In a seaplane, the combination with a pontoon, of a landing wheel normally housed therein, a pair of casings mounted on the pontoon having longitudinal slots in their opposed sides, a fluid-pressure cylinder disposed between the casings, projections on the cylinder extending through the slots in the casings, expansion springs in the casings above and below said projections, and a piston mounted in the cylinder and operatively connected with the landing wheel.

In testimony whereof I affix my signature.
